COMB

John W. Kaye, San Antonio, Tex.

Application November 3, 1949, Serial No. 125,305

7 Claims. (Cl. 132—19)

1

This invention relates to new and useful improvements in combs.

One object of the invention is to provide an improved comb having means for dressing and treating a user's hair as the comb is used, such dressing and treating being of the nature of that imparted by brushing on the hair.

Another object of the invention is to provide an improved comb which eliminates the usual tendency, common to nearly all combs of the ordinary variety, to curl or kink the strands of hair in an objectionable manner.

A construction designed to carry out the invention will be hereinafter described together with other features of the invention.

The invention will be more readily understood from a reading of the following specification and by reference to the accompanying drawing, wherein examples of the invention are shown, and wherein:

Fig. 1 is a view in elevation of a comb constructed in accordance with this invention,

Fig. 2 is a vertical, sectional view taken on the line 2—2 of Fig. 1,

Fig. 3 is a view in elevation of a modification of the invention,

Fig. 4 is a vertical, sectional view taken on the line 4—4 of Fig. 3, and,

Figs. 5 and 6 are perspective views of further modifications of the invention.

An ordinary comb has a tendency in use to curl or kink strands of hair much in the manner which may be observed by drawing a single hair between the one's thumbnail and the fleshy part of the forefinger. It is believed that this undesirably tendency arises through bunching of the hair at the upper ends of the comb teeth adjacent the back or body of the comb whereby the movement of the hair between the teeth is hindered, and the drawing of the hair under this applied tension over the edges of the comb back. This drawing of the hair under a stress over a relatively angular or sharp edge is injurious to the individual strands of hair, tends to destroy permanent waving of the hair, and increases the difficulty of persuading the hair to lie naturally upon a person's head. The present invention eliminates these objections by providing a roller over which the hair passes.

In the embodiments illustrated in the drawing, the numeral 10 designates a comb having an elongate back or body 11 with a plurality of teeth 12 extending from one longitudinal edge thereof. In the form of the invention shown in Fig. 1, an elongate rectangular recess or pocket 13 is formed in the opposite longitudinal edge of the body 11

and extends from a point adjacent one end to the body to the medial portion thereof. A slim, cylindrical roller 14 is positioned within the recess and rotatably mounted upon pins 15 extending from each end of the roller into the body of the comb. The roller is thus arranged with its axis substantially parallel to the longitudinal dimension of the comb body and is free to revolve within the recess 13 of the latter.

The diameter of the roller is somewhat greater than the thickness of the comb body whereby the surface or periphery of the roller projects laterally beyond each side of the comb body. With this arrangement, strands of hair being combed are caused to pass over the roller rather than over the stationary side of the comb body, and the revolving of the roller with the passage of the hair eliminates all scraping, undue stretching, and physical abuse of the hair strands. The dressing and treating of the hair, inherent in the combing process, is retained, but damaging the hair strands is avoided.

It is further to be noted that the positioning of the pins 14 causes the roller also to project beyond the upper longitudinal edge of the comb body, as shown in Fig. 2, whereby substantially all contact between the hair and the comb body is eliminated. Even though the comb is turned by the user until the teeth point away from the user's head, there will be no drawing or scraping of the hair strands across an edge or corner of the comb body.

A modification of the invention is shown in Figs. 3 and 4 of the drawing. In this form, the comb body 11 is provided with an elongate rectangular window or opening 16 cut in the body adjacent the longitudinal edge thereof opposite the tooth-carrying edge. The roller 14 is mounted within the opening 16 upon the pins 15 similarly to the mounting of the previously described modification, and is free to revolve with respect to the comb body. The periphery of the roller projects laterally beyond each side of the body (Fig. 4) so as to receive the strands of hair engaged between the teeth 12.

The invention is not to be limited to a roller extending only one-half the length of the comb since it may be continued throughout substantially the entire length of the comb body as shown by the roller 17, illustrated in Fig. 5 as mounted within an elongated recess 18 cut in the body 11. Further, the surface of the roller may be ribbed or fluted as exemplified by the roller 19 of Fig. 6, or carry other surface irregularities enhancing its engagement with the hair.

The foregoing description of the invention is

explanatory thereof and various changes in the size, shape and materials, as well as in the details of the illustrated construction may be made, within the scope of the appended claims, without departing from the spirit of the invention.

What I claim and desire to secure by Letters Patent is:

1. A comb including, an elongate body, teeth extending from the body, the body having an elongate opening extending transversely there-through, and an elongate roller rotatably mounted in said opening with its axis substantially parallel to the longitudinal axis of the body, a portion of the periphery of the roller projecting outwardly beyond the body.

2. A comb including, an elongate body, teeth extending from one longitudinal edge of the body, the opposite longitudinal edge of the body having an elongate recess cut therein, and an elongate roller rotatably mounted in said recess with its axis substantially parallel to the longitudinal axis of the body, a portion of the periphery of the roller projecting outwardly beyond the body.

3. A comb including, an elongate relatively flat comb body having a back and teeth extending from the back, and a roller rotatably mounted in the back so that a portion of the peripheral surface of the roller projects laterally of the back,

the axis of the roller being substantially parallel to the longitudinal axis of the comb body.

4. A comb as set forth in claim 3 wherein portions of the peripheral surface of the roller project laterally from each side of the back.

5. A comb as set forth in claim 3 wherein the roller extends throughout substantially the entire length of the body.

6. A comb as set forth in claim 3 wherein the roller is grooved.

7. A comb including, an elongate relatively flat comb body having a back and teeth extending from the back, a portion of the back being cut away, and an elongate roller rotatably mounted in said cut away portion of the back with its axis substantially parallel to the longitudinal axis of the comb body, a portion of the peripheral surface of the roller projecting laterally of the back.
